(57) **CLAIM**

The ornamental design for a bracket to connect antenna lead and dipole lines, as shown and described.

DESCRIPTION

FIG. 1 is a front, left side, bottom perspective view of a bracket to connect antenna lead and dipole lines showing my new design;

FIG. 2 is a front elevational view thereof;

FIG. 3 is a right side elevational view thereof, the left side being identical to FIG. 3;

FIG. 4 is a rear elevational view thereof;

FIG. 5 is a top plan view thereof; and,

FIG. 6 is a bottom plan view thereof.
